United States Patent Office

Des. 221,601
Patented Aug. 24, 1971

221,601

PAPERWEIGHT

Varkis A. Markarian, 3 Applegate Road,
Cranston, R.I. 02920

Filed May 18, 1970, Ser. No. 23,033

Term of patent 14 years

Int. Cl. D19—02

U.S. Cl. D74—12

FIG. 1

FIG. 2

FIG. 3

FIG. 4

FIG. 5

FIG. 6

FIG. 1 is a front elevation of a paperweight embodying my new design;

FIG. 2 is a right edge view thereof;

FIG. 3 is a rear view thereof;

FIG. 4 is an edge view thereof from the side opposite FIG. 2;

FIG. 5 is a bottom view thereof; and

FIG. 6 is a top plan view thereof.

I claim:

The ornamental design for a paperweight, as shown.
